Primary Examiner — Mark A Goodwin(74) *Attorney, Agent, or Firm* — WHDA, LLP(57) **CLAIM**

The ornamental design for an electric riding lawn mower, as shown and described.

DESCRIPTION

FIG. 1 is a first right side perspective view of an electric riding lawn mower showing my new design;

FIG. 2 is a first left side perspective view thereof;

FIG. 3 is a second right side perspective view thereof;

FIG. 4 is a second left side perspective view thereof;

FIG. 5 is a front view thereof;

FIG. 6 is a rear view thereof;

FIG. 7 is a right side view thereof;

FIG. 8 is a left side view thereof;

FIG. 9 is a top plan view thereof; and,

FIG. 10 is a bottom view thereof.

The broken lines in the drawings illustrate portions of the electric riding lawn mower that form no part of the claimed design.
